CLASP FOR RECEPTACLES

William H. Meincke, White Plains, N. Y.

Application December 21, 1938, Serial No. 246,957

2 Claims. (Cl. 292—254)

This invention relates to receptacles and their covers and more particularly it pertains to a novel construction of clasp for holding the covers in their closed position and providing novel means for operating such clasp.

In the accompanying drawing, the invention has been illustrated as embodied in a receptacle of the cigarette case type and while it particularly lends itself to this type of receptacle, it is also capable of use in connection with receptacles of other types and is, therefore, not to be limited to the embodiment in which it is herein illustrated.

Cases of the type illustrated are particularly awkward to open. As generally constructed, they are held closed by a clasp which is released by application of pressure upon a thumb or finger member which projects from one of the case or receptacle members.

It often happens, in grasping the case to open it, that the thumb or finger piece falls upon the wrong side and the case member, by which it is carried, is not, therefore, free to move to open position by reason of engagement of the thumb or finger therewith. When this condition exists, the person using the device either has to reverse its position in the hand by which it is grasped, or transfer it to the other hand, either of which is annoying and it generally results in the person using the case, resorting to the use of both hands to effect an opening thereof.

It is the primary object of the invention to provide a new and novel construction of clasp which will eliminate the several disadvantages aforementioned as prevalent in such devices of the conventional construction.

A feature of the invention resides in a novel construction of operating means for the clasp whereby the same may be operated by either hand in either position.

A further feature of the invention resides in the novel arrangement and construction whereby that member of the case which is disposed outwardly with respect to the palm of the hand, will be free to move to open position without interference on the part of the thumb or finger by which the clasp of the case has been operated.

Other features and objects of the invention will become apparent as the nature thereof is better understood and for this purpose, reference will be had to the following specification and claims and the accompanying drawing, in which,

Figure 1 is a perspective view of a cigarette case having a clasp and operating means con-

structed in accordance with the present invention.

Figure 2 is a view in elevation illustrating one manner of use of such a case,

Figure 3 is a detail sectional view on an enlarged scale, taken substantially on the line 3—3 of Figure 1,

Figure 4 is a fragmentary longitudinal sectional view taken substantially on the line 4—4 of Figure 1, the view being upon an enlarged scale,

Figure 5 is a detail sectional view taken substantially on the line 5—5 of Figure 3,

Figure 6 is a detail sectional view on an enlarged scale, taken substantially on the line 6—6 of Figure 1, and

Figure 7 is a detail perspective view of the double clasp.

The receptacle, which as heretofore stated is of the cigarette case type and it comprises two members 10 and 12 which are hingedly connected together as at 13 in any conventional manner, and preferably includes a spring which tends normally to move the members 10 and 12 to their open position.

The meeting edges of the members 10 and 12, except of course the meeting edges by which they are hingedly connected together are provided with inwardly turned flanges 16 both to provide a sift-proof joint between the members 10 and 12 and to provide a finish for said joint.

As best illustrated in Figure 3, the member 12 carries a catch 18 which has a shoulder 20 for engagement behind the inturned flange 16 of the member 10. The catch 18 is mounted rigidly upon a resilient member 22 which in turn is rigidly secured to the member 12 at a point behind the inturned flange 16 thereof. A portion 24 of the clasp projects through an opening 26 in the inturned flange of the member 12 and forms a thumb or finger operating member for the clasp.

By reference to Figure 3, it will be obvious that pressure applied to the operating member 24, will flex the spring 22 and move the catch 20 out of engagement with the inturned flange of the member 10, permitting the members 10 and 12 to move to their open position.

So far as described, the construction is conventional. However, it will be obvious that if such a device is grasped in the manner illustrated in Figure 2, pressure applied to the clasp operating member 24 by the thumb, will by reason of engagement of the thumb with said operating member prevent, or at least interfere with free

movement of the members 10 and 12 to their open position. By the same token, free and easy movement of the members 10 and 12 is interfered with if the device is grasped in the right hand 5 with the member 12 disposed outwardly with respect to the palm of the hand.

In accordance with the present invention, I provide a second operating member in the form of a thumb or finger element 30 carried by the member 10 of the receptacle and so positioned thereon as to be slightly spaced with respect to the operating member 24 carried by the member 12.

This operating member 30 is rigidly mounted 15 upon a resilient member 32 which in turn is rigidly connected at one end to the member 10 by which it is carried.

As best illustrated in Figures 3 and 7, this operating member 30 has an extension 34 which over- 20 lies the shoulder 20 of the clasp 18.

By this construction, it will be apparent that when pressure is applied to the operating member 24, the clasp 18 will be depressed out of engagement with the inturned flange 16 of the member 10 and will permit the members 10 and 12 to move to their open positions. During such 25 operation, the shoulder 20 of the clasp 18 merely moves away from the extension 34 of the operating member 30. The foregoing operation, 30 would of course be the result when the case is grasped in either hand with the member 12 disposed inwardly towards the palm of the hand. When, however, the case is grasped in either hand with the member 10 disposed inwardly or 35 towards the palm of the hand, pressure is applied to the operating member 30 whereupon, its extension 34 will act to disengage the clasp 18 from the inturned flange 16 of the member 10 and permit the members 10 and 12 to move freely to their open position.

Thus it will be apparent that regardless of which of the two members 10 and 12 is disposed inwardly with relation to the palm of the hand by which the device may be grasped, the clasp 18 45 may be disengaged with the inturned flange of the member 10 in such a manner that the outer member is free to move to position to open the case without interference upon the part of the thumb or finger by which said pressure is applied.

From the foregoing, it will become readily apparent that the several objects of the invention are attained by the construction herein set forth.

It is to be understood however, that the invention is not limited to the specific construction herein shown and that it may be carried out in such other forms as rightfully fall within the scope of the appended claims.

Having thus described the invention, what is claimed as new, is:

1. A latch for cases and the like of the type comprising two hingedly connected members, said latch comprising a hooked member carried by one of the case members for engagement with the other case member to retain the case members in their closed position, a resilient element secured at one of its ends to one of the case members and having its other end free, said hooked member being carried by said resilient element upon the free end thereof, means carried by said resilient element for disengaging the hooked member against the tension of the resilient element to permit of relative movement of the hingedly connected case members, and separate means carried by the other of the hingedly connected case members for engagement with the hooked member to operate the hooked member independently of the first mentioned operating means.

2. A latch for cases and the like of the type comprising two hingedly connected members, said latch comprising a hooked member carried by one of the case members for engagement with the other case member to retain the case members in their closed position, a resilient element secured at one of its ends to one of the case members and having its other end free, said hooked member being carried by said resilient element upon the free end thereof, means carried by said resilient element for disengaging the hooked member against the tension of the resilient element to permit of relative movement of the hingedly connected case members, and separate means carried by the other of the hingedly connected case members for engagement with the hooked member to operate the hooked member independently of the first mentioned operating means, said separate operating means comprising a resilient element secured to that case member which is engaged by the hooked member, said resilient element having a free end overlying the hooked member and an operating member for said second mentioned resilient member.

WILLIAM H. MEINCKE.
